UNITED STATES PATENT OFFICE

2,588,603

STRAPLESS BRASSIÈRE

Margaret K. Anderson, Beverly Hills, Calif., assignor to Helene Brassiere Company, Inc., Glendale, Calif., a corporation of California

Application April 23, 1949, Serial No. 89,333

1 Claim. (Cl. 2—42)

1
This invention relates to improvements in brassière construction and is particularly directed to a brassière capable of being worn without the use of shoulder straps.

The term "brassière" as employed herein relates to any breast-receiving and covering garment whether such garment is an integral part of an outer garment or a separate under garment. The construction of the present invention may be used in an under garment or it may be embodied in bathing suits, sun suits or various other articles of clothing.

Heretofore brassières generally stated comprised a garment capable of encircling the body in the region of the breasts, such garment being supported by shoulder straps each of said straps extending over a shoulder and connecting the upper marginal edge of the brassière with the rear portion of the band. Shoulder straps are unsightly in certain instances and detract from shoulder contours. Moreover the usual type of brassière cannot be worn with certain evening gowns.

Strapless brassières have been constructed heretofore but have necessitated the use of many reinforcing elements such as bones, strips, etc. Moreover, most of the strapless brassières known to me either included a relatively wide body band below the breast-receiving cups or have been incapable of maintaining their position upon the body. The use of a wide band beneath the breast cups is unsatisfactory since it prevents the use of such construction in what is known as "bare midriff dresses" and in certain types of bathing suits and sun suits. Since most of these prior brassières depended solely upon the constricting influence of the band to maintain the position of the brassière upon the body they either could not be worn with comfort or had a highly developed tendency to slip downwardly along the body of the wearer.

These various disadvantages of prior constructions are overcome by means of the present invention. Generally stated the construction hereinafter disclosed in greater detail includes the provision of a single, preferably unitary formed wire element having a central, substantially horizontal portion connecting two virtually semi-circular sections, these semi-circular sections partially encircling the inner and upper portions of each breast. The inner and upper margins of each breast-receiving cup are delineated by and attached to the virtually semi-circular sections of the wire element. In the preferred form the semi-circular sections are essentially formed

so as to have portions thereof overlap or at least be in close proximity. When the garment is applied to the body and the elastic band portions of the brassière are connected the central portion of the wire element imparts resiliency to the entire structure, the semi-circular sections of the wire element permitting outward movement of the two breast-receiving cups carried thereby. The wire element not only contributes to the resiliency of the entire brassière but also anchors the brassière upon the body of the wearer preventing undesirable downward movement.

It is an object of the present invention therefore to disclose and provide an improved brassière construction wherein a wire element joins the breast-receiving pockets, partially encircles each of such pockets and imparts form-fitting characteristics thereto.

Another object of the invention is to disclose and provide an improved strapless brassière.

A still further object of the invention is to disclose and provide a pre-formed resilient wire element for use in brassières. These and other objects and advantages of the present invention will become apparent to those skilled in the art of brassière manufacture from the following description. For purposes of illustration reference will be had to the appended drawings in which:

Fig. 1 is a perspective three-quarter front view of a brassière embodying the present construction in position upon the body of the wearer.

Fig. 2 is a front view of one form of wire element utilized in the brassière shown in Fig. 1.

Fig. 3 is an end view of the wire element shown in Fig. 2.

Fig. 4 is an enlarged section taken through the upper marginal edge of a breast-receiving pocket.

Fig. 5 is a front view of a modified form of brassière, in extended form.

The brassière illustrated in Fig. 1 comprises two breast-receiving cups 10 and 11 the outer side of such cups being connected to a short outer underarm member such as 12 and a rearwardly extending elastic band portion 13, the band portions being provided with means for their connection in the central portion of the back of the wearer, as is customary. The breast-receiving cups 10 and 11 may be made in any suitable manner from two, three, four, or any number of pieces of material and the material employed may vary with the desires of the manufacturer, the price to be charged, etc.

It will be noted that the side members 12 are each provided with a relatively narrow bottom band or band portion 14. The inward ends 15 of

the band portions 14 are spaced from each other and such ends 15 are located beneath the breast-receiving cups. Connection is established between the two cups 10 and 11 by means of a relatively straight substantially horizontal portion 16, this portion 16 being the central portion of a pre-formed wire element generally indicated by a heavy, dotted line at 9.

The preferred configuration of the preformed wire element 9 is best illustrated in Figs. 2 and 3. As there shown the central substantially horizontal portion 16 is provided with upstanding end portions 17 and 17' each of said end portions being preferably of shorter length than the length of the central portion 16. A virtually semi-circular section extends from the upper end of the end portions. These curved sections are indicated at 18 and 18' and it will be noted that each of these curved sections terminates in a blunt or turned-back end such as 19 which is spaced from and displaced outwardly from the upper end of its correlated end portion 17.

It is to be understood that Fig. 2 shows the resilient wire element in its normal relaxed position. In this relaxed position it will be noted that intermediate portions of the sections 18 and 18' are in overlapped relation. Furthermore, as best shown in Fig. 3, the terminals 19 and a part of the semi-circular section leading thereto is displaced rearwardly out of the plane normally occupied by the central portion 16 and the upstanding portions 17 and 17' of the element.

The entire wire element 9 is preferably covered with a plush tape or tubing so as to enclose such element. The breast-receiving cups 10 and 11 are attached to such plush tubing and to the adjacent outward portions 12. The upstanding end portions 17 and 17' of the element are connected to the ends 15 of the short band elements 14. The ends 15 of the bands 14 may be provided with a loop through which the upstanding end portions 17 of the wire element may pass.

When the brassière is placed upon the body and the opposing ends of the resilient or elastic band members 13 are connected a rearward stress is applied to each of the portions 12 of the brassière and transmitted thereby to the terminals 19 of the formed element 9. In order to equalize this rearward tension and prevent undesirable cupping or bulging of the garment in the under-arm zone a stiffening element such as a rib or bone 22 is built into the rear area or margin of each of the members 12. This reinforcing rib or bone is preferably at an upwardly and outwardly inclined angle to the bottom edge of the band 14. Moreover, such bone or reinforcing 22 should be in relatively close proximity to the outer edge of the adjacent breast-receiving cup 10. Normally it has been found desirable to have such reinforcing or bone positioned at a distance of from one-half inch to one and one-half inches of the adjacent margin of the breast-receiving cup.

The outwardly directed tension transmitted by the resilient band members 13 to the brassière and distributed by the reinforcing or bone 22 deflects the terminal 19 of the pre-formed wire member into the wash-line portion indicated in Fig. 2. It will be noted that in this position the two virtually semi-circular sections 18 and 18' are spaced from each other. It will also be noted that the central and lower portion 16 becomes arched. As a result the breast-receiving cups 10 and 11 assume a natural spaced position upon the body and the body of the wearer is exposed between the breasts to a point materially below

the breasts. Such plunging neckline is highly desirable for many evening gowns.

It may also be noted that the garment is comfortable to wear inasmuch as it expands and contracts with breathing such resiliency being imparted not only by the bands 13 but also by the resiliency of the central section 16. Since portions of the wire element extend over the top of each breast the garment will not slip downwardly. Moreover, since a portion of each of the wire elements extends beneath each breast-receiving pocket displacement of the garment upon the body of the wearer is prevented and the accidental downward movement of the breast from beneath the brassière is inhibited.

Although the brassière is primarily to be used without shoulder straps, means can be provided for the selective attachment of shoulder straps to the brassière. As best shown in Fig. 4 (which is a transverse section through an upper marginal edge portion of the breast cup 10) the curved portion 18 of the wire frame may be retained between a backing tape 23 and the plush tape 24, this assembly being connected to the marginal portion of the breast cup 10. A small length of ribbon 25 may be carried on the surface of the tape 24, the entire assembly being stitched as by lines of stitching 27 and 28. The hook 29 of a strap fitting 30 can be selectively inserted beneath the ribbon 25 whenever the wearer desires to use shoulder straps. The rear elastic members 13 may be similarly provided with ribbon loops for the purpose of releasably connecting the rear ends of the shoulder straps therewith. The ribbon members 25 are preferably located in the upper portions of the breast cups spaced from the terminals 19 of the contained pre-formed wire element.

Fig. 5 illustrates a modification wherein the wire element is provided with longer upstanding portions 37 and 37'. The curved sections 38 and 38' normally do not overlap and a sternum piece 26 extends over the area between the central bottom portion 36, the upstanding portions 37 and the opposing lower portions of the sections 38. A brassière constructed in accordance with this modification does not expose the body of the wearer between the breasts but the wire framework insures close contact of all portions of the brassière with the body, prevents slippage of the garment upon the body and permits its use without shoulder straps.

It is to be understood that the breast-receiving cups may be made of any conformable material so arranged as to impart the desired contours to the breast (generally somewhat conical in form). The under-arm portions 12 as well as the band 14 may be made of any compliant fabric whereas the rearwardly extending band portions are of elastic stitchable material. The breast-receiving cups may be stitched or decorated in any suitable manner for decorative and reinforcing purposes.

All changes and modifications coming within the scope of the appended claim are embraced thereby.

I claim:

In a brassière including a pair of virtually conical breast-receiving cups of compliant material, the provision of: a resilient wire element consisting of a substantially horizontal central section, each end section of the element being curved into a substantially semicircular form, and an upstanding, intermediate section between each of said curved end sections and the central

section; each of the curved end sections including a portion, adjacent the associated intermediate section, directed inwardly toward the other curved end section, and an end portion directed away from the other curved end section; each of the curved end sections being preformed and prestressed, one of the curved end sections lying in the plane of the central section and the other out of the plane thereof and in partial overlapping relation when in normal position off the body of a wearer; each of the curved sections of the wire element being attached to a breast-receiving cup; and a rearwardly extending underarm portion including elastic, stretchable means, connected to the outward margin of each cup, said rearwardly extending portions being adapted to encircle the body and be joined and to hold the breast-receiving cups in spaced posi-

tion against the prestressed wire element, whereby the body of the wearer is exposed between said cups.

MARGARET K. ANDERSON.
